TETRAHEDRAL SHAPED CONTAINER

William S. Schneider, Glendale, Calif., assignor, by mesne assignments, to Ultra-Pak, Inc., Boston, Mass., a corporation of Massachusetts

Filed Feb. 27, 1959, Ser. No. 54,776

Term of patent 14 years

(Cl. D58—2)

FIG. 1 is a top perspective view of a tetrahedral shaped container showing my design.

FIG. 2 is a side elevation thereof viewed from the left of FIG. 1.

FIG. 3 is a top plan view thereof.

FIG. 4 is a side elevation viewed from the left of FIG. 2.

FIG. 5 is a bottom plan view thereof.

I claim:

The ornamental design for a tetrahedral shaped container, as shown.
